CIRCUIT CONTROLLING MEANS

Herbert L. Bone, Forest Hills, Pa., assignor to
The Union Switch & Signal Company, Swiss-
vale, Pa., a corporation of Pennsylvania

Application November 28, 1944, Serial No. 565,547

5 Claims. (Cl. 200—51)

1

My invention relates to circuit controlling means, and particularly to circuit controlling means for disengaging external electrical circuits and for operating internal electrical circuits on an electrically controlled missile, such for example, as a certain special type of bomb carried by airplanes, when the missile is released toward its ultimate target.

One object of my invention is to provide circuit controlling means of the type described which can be set and sealed in an unarmed position until the device is mounted upon the desired launching means and the usual arming means, such as an arming wire is applied, and which will automatically assume an armed position upon the withdrawal of the usual arming means.

Another object of my invention is to provide a circuit controlling means of the type described which will be inexpensive to manufacture, and will at the same time safely and reliably perform its intended functions.

According to my invention, the circuit controlling means comprises a plug member, commonly referred to as a "kick-off" plug, provided at one end with a plurality of projecting contact fingers adapted to cooperate with the contact members of a standard plug connector permanently connected by means of a flexible cable to the wiring of the launching device upon which the missile is to be mounted prior to its release toward its ultimate target. The kick-off plug is constructed to fit loosely inside a supporting member permanently secured to the side of the missile, and is arranged to be held in a fixed or unarmed position in this member by means of a seal pin until the missile is mounted on the device from which it is to be launched, whereupon the seal pin is replaced by the usual arming wire in accordance with standard practice. The kick-off plug at the end opposite to the projecting contact fingers is provided with a plurality of contact buttons disposed in recesses in the plug and each connected to a different one of the projecting contact fingers. Each of these contact buttons cooperates with one end of an associated contact post slidably mounted in a supporting member also attached to the missile. The contact posts are biased into engagement with the contact buttons of the plug by means of springs which not only serve to provide good contact pressure between the contact posts and the contact buttons of the plug but which also serve to develop a sizable force on the plug sufficient to eject it upon removal of the arming wire. Certain ones of the posts engage movable contact fingers forming part of an associated stack of contacts in such manner that the posts not only make contact with the fingers but also serve to move them to actuate the associated

2

stack of contacts upon release of the kick-off plug. The other posts are electrically connected by means of flexible leads with certain other contact members disposed in the contact stack.

5 Other objects and characteristic features of my invention will become apparent as the description proceeds.

I shall describe one form of circuit controlling means embodying my invention, and shall then 10 point out the novel features thereof in claims.

In the accompanying drawings, Figs. 1, 2 and 3 are top plan, left-hand and right-hand end views, respectively, showing one form of circuit controlling means embodying my invention. 15 Figs. 4 and 5 are sectional views taken substantially on the lines IV—IV and V—V, respectively, of Fig. 1. Figs. 6 and 7 are opposite end views of a plug part 1 forming part of the circuit controlling means embodying my invention.

20 Similar reference characters refer to similar parts in each of the several views.

Referring to the drawings, the circuit controlling means in the form here illustrated comprises a plug part 1 which cooperates at one end 25 with a plug connector 2, and at the other end with a plurality of movable terminal posts forming part of an electrical switching means S.

The plug part 1, shown in detail in Figs. 4, 5, 6 and 7, is commonly referred to as a "kick-off" 30 plug for reasons which will appear presently, and comprises a cylindrical block of insulating material provided with four longitudinally extending holes 3, 4, 5 and 6 terminating at one end in two transverse grooves 8 and 9, and counter-bored at the other end to form recesses 3a, 4a, 5a and 6a, respectively. The holes 3, 4, 5 and 6 receive contact pins 10, 11, 12 and 13. These pins are provided at one end with enlarged heads 10a, 11a, 12a and 13a, respectively, disposed in 35 the recesses 3a, 4a, 5a and 6a, and are secured at the opposite ends, as by riveting, to projecting contact fingers 10b, 11b, 12b and 13b. The heads 10a, 11a, 12a and 13a constitute contact buttons 40 for cooperation with the ends of the previously referred to terminal posts, as will be explained in more detail hereinafter, while the contact fingers 10b, 11b, 12b and 13b are intended to be plugged into cooperating female contact members 45 forming part of the plug connector 2.

The plug connector 2 is a standard piece of electrical equipment sold commercially as a "Jones" plug, and for purposes of my present invention it is sufficient to point out that the 55 contact members of this plug connector are electrically connected to circuit wires comprising a flexible cable forming part of the permanent wiring of the launching device upon which the missile provided with the circuit controlling means embodying my invention is to be mounted im-

mediately prior to its release to its ultimate target.

It should be particularly noted that two of the projecting contact fingers 10b and 11b of the plug part 1 are disposed at right angles to the other two contact fingers 12b and 13b, so that it is impossible to plug the plug part into the plug connector 2 except in one relative position, thus insuring that it is impossible to make improper electrical connection between the missile and the wiring of the launching device. It should also be noted that two of the holes 3 and 4 in the plug part 1 are spaced closer together than the other two holes 5 and 6 to polarize the opposite end of the plug.

It will be observed that the projecting contact fingers are held in the desired angular positions relative to the plug part 1 by engagement of enlarged end portions of the fingers with the sides of the grooves 8 and 9.

The plug part 1 is provided, in addition to the transversely extending grooves 8 and 9, with a longitudinally extending groove 14, and in addition to the four longitudinally extending holes 3, 4, 5 and 6, with two other transverse holes 15 and 16 disposed between the holes 3 and 6 and the holes 4 and 5, respectively. The function of the groove 14, and the functions of the holes 15 and 16 will be made clear presently.

The diameter of the plug part 1 is such that it will fit loosely within a cylindrical supporting member 17 which is secured to the outer side of any desired portion 20 of the missile for which the circuit controlling means embodying my invention is provided. In the case of certain forms of electrically controlled bombs for which my circuit controlling means is particularly suitable, the portion 20 may comprise a shell which fastens to the end of the bomb. A hole 20a is formed in the shell 20 to receive the inner ends of the supporting member 17 and the plug part 1.

The plug part 1 is prevented from being inserted into the supporting member 17 except in one relative angular position by means of a pin 21 which cooperates with the groove 14 in the plug, and is arranged to be held in the desired longitudinal position in the supporting member 17, prior to mounting the missile on the launching device, by means of a seal pin 22 which passes through the hole 15 in the plug and through aligned holes 17a provided in the supporting member. When the missile is mounted on the launching device an arming wire 22a shown in dot and dash lines in Fig. 5, is then inserted through the hole 16 in the plug part 1 and through aligned holes 17b provided in the supporting member 17 and the seal pin is removed. The arming wire is smaller in diameter than the seal pin, and the hole 16 in the plug is accordingly made smaller than the hole 15 for the reception of the seal pin. The fact that the hole 16 is smaller than the hole 15 prevents the insertion of the seal pin in the wrong set of holes. The parts are so proportioned that the plug will be held in approximately the same position in the supporting member by either the seal pin or the arming wire. As long as the plug is in place in the supporting member the missile is said to be in an unarmed condition.

The terminal posts referred to hereinbefore as forming part of the switching means S, are designated 25, 26, 27 and 28, respectively. These terminal posts are slidably mounted at one end in clearance holes 25a, 26a, 27a and 28a provided in a mounting plate 29, and at the other end in

clearance holes in insulating bushings 30 mounted in a U-shaped supporting bracket 31 secured by means of screws 32 to the mounting plate 29. The mounting plate is of suitable insulating material such as "micarta." The terminal posts are provided intermediate their ends with enlarged portions 25b, 26b, 27b and 28b and interposed between these enlarged portions and flanges formed on the inner ends of the insulating bushings 30 are compressed coil springs 25c, 26c, 27c and 28c which bias the terminal posts to the longitudinal positions in which the enlarged portions engage the mounting plate 29. In these positions of the contact posts, the ends of the posts project through the mounting plate 29 and the hole 20a in the shell 20 for a distance which is considerably greater than the distance from the underside of the mounting plate to the enlarged heads or contact buttons 10a, 11a, 12a and 13a of the contact pins 10, 11, 12 and 13 when the plug part 1 is in the armed position in which it is shown in Figs. 4 and 5, and it will be obvious therefore that when the plug part is in its armed position, the heads of the contact pins will engage the ends of the terminal posts and will move the contact posts upwardly in opposition to the bias of the associated springs to the positions shown in Figs. 4 and 5, whereby the springs 25c, 26c, 27c and 28c not only serve to provide good contact pressure between the contact posts and the contact buttons of the plug but also serve to develop a sizable force on the plug sufficient to kick it out of the supporting member 17 upon removal of the arming wire. The arming wire is held by the device which releases the missile in such manner that the arming wire will be automatically withdrawn from the holes 16 and 17b when the missile first starts to move, and it follows, therefore, that with circuit controlling means embodying my invention the plug part 1 will automatically be kicked off of the missile as it is released toward its ultimate target. There is sufficient slack in the cable attached to the plug connectors 2 to insure that the kicking off of the plug part 1 will not cause any strain on the cable.

The switching means S also comprises two stacks of contacts designated A and B respectively in the drawing. The stack A is shown in detail in Fig. 4, and comprises a plurality of movable contact fingers 35, 36 and 37 which cooperate with fixed contact fingers 35a, 36a and 37a, respectively, to form contacts 35-35a, 36-36a and 37-37a. The fixed and movable contact fingers are clamped in superposed parallel spaced relation between insulating blocks 38 secured by means of screws 39 to the mounting plate 29, and associated with each of the fingers with the exception of the finger 35 is a reinforcing spring 40 which serves to increase the contact pressure exerted by the contacts when they are closed. Also associated with the fixed contact fingers 35a, 36a and 37a are fixed stops 35b, 36b and 37b which are arranged to limit the movement of the associated fingers toward the stops. The screws 39 are insulated from the various fingers, reinforcing strips and stops by means of insulating bushings 41 which surround the screws.

The lower movable finger 35 is made longer than the other fingers and is provided at its free end with a slotted portion 35d the slot of which receives the terminal post 27 with some clearance between the spring 27c and the enlarged portion 27b of the post, whereby the finger 35 is both mechanically and electrically connected with the

contact post 27. An L-shaped insulating member 36c is secured to the free end of the finger 36 and serves to operatively connect this finger with the finger 35. A similar L-shaped insulating member 37c is secured to the free end of the finger 37 and operatively connects this latter finger with the finger 36. The parts are so proportioned that when the post 27 is moved to the position to which it is biased by the spring 27c, the contacts 35-35a, 36-36a and 37-37a will all be closed, but that, when the kick-off plug is in place in the member 17 as shown in Fig. 4, the fingers 35, 36 and 37 will all be moved upwardly in a manner which will be obvious from an inspection of the drawing to the positions in which the contacts 35-35a, 36-36a and 37-37a are all open.

The stack 3 is shown in Fig. 5 and comprises a movable contact finger 42, a fixed contact finger 43, and a movable contact finger 44 clamped in superposed parallel spaced relation between insulating blocks 45 secured to the mounting plate 29 by means of screws 46. The movable finger 42 is provided at its free end with a slotted portion 42a the slot of which receives with some clearance the contact post 28 between the spring 28c and the enlarged portion 28b of the post 28, whereby this finger is both mechanically and electrically connected with the post 28. The movable finger 44 is operatively connected with finger 42 by means of an L-shaped insulating member 44a and cooperates with the finger 43 to form a contact 43-44. The parts are so proportioned that this contact will be closed or open according as the contact post 28 occupies the position to which it is biased by the associated spring 28c or the position to which it is moved when the plug 1 is in place in the supporting member 17. Stiffening springs 49 are inserted in the stack below and above the fingers 43 and 44 respectively to increase the contact pressure when the contact 43-44 is closed, and a fixed stop 50 is inserted in the stack A above the fixed finger 43 to limit the upward movement of this finger to determine the point in the stroke of the contact post 28 at which the contact 43-44 will open. The screws 46 are surrounded by insulated bushings 52 which insulate the screws from the various members of the stack.

The movable contact post 25 is connected by means of a flexible lead 51 to a terminal strip 57 mounted in the stack below the finger 42, and the movable post 26 is connected by means of a flexible lead 53 with a terminal strip 54 clamped in the stack A in contact with the movable finger 38.

The rear ends of the various fingers in both contact stacks project beyond the associated clamping blocks and are provided with through holes to facilitate soldering circuit wires to the fingers.

The operation as a whole of the circuit controlling means embodying my invention is as follows: When the missile to which the circuit controlling means is attached is unarmed the "kick-off" plug is secured in place in the supporting member 17 by the seal pin, and a suitable seal 56 is placed through the small hole in the small end of the seal pin to secure the seal pin in place. Under these conditions, all parts occupy the positions in which they are shown in Figs. 4 and 5, and it will be obvious, therefore, that when the missile is not ready to be launched the contacts of the switching means S are all open.

When the missile is being made ready for use the arming wire 22a is first inserted through the hole 15 in the plug and the aligned holes 17b in the supporting member 17, and the seal is then

broken in the seal pin and the seal pin is withdrawn from the plug and the associated supporting member. The presence of the arming wire in the plug holds the parts in the same positions which they occupied while the seal pin was in place. After the plug connector 2 is plugged into the plug part 1 the missile is then ready to be released.

When the missile is released, the arming wire is withdrawn from the supporting member 17 and the plug part 1, and the plug part 1, due to the bias of the springs 25c, 26c, 27c and 28c, is forcibly ejected from the supporting member 17. The ejection of the plug part 1 disengages the external circuits from the missile and permits the contacts of the switching means S to move to their closed positions to thereby operate the internal circuits of the missile. The forcible ejection of the "kick-off" plug throws it clear of the missile before the missile has moved far enough to take up the slack in the cable attached to the plug connector 2, and thus prevents the placing of any strain on the permanent wiring of the launching device which might affect the subsequent operation of the launching device.

It should be particularly pointed out that while in describing my invention I have shown only one contact combination for the switching means S, this particular contact combination is not essential to my invention and can readily be varied in accordance with well known practice. It should also be pointed out that while the circuit controlling means described makes provision for connecting only four external circuit wires with the internal wiring of the missile for which the circuit controlling means are provided, additional external circuit connections can likewise readily be provided in an obvious manner.

Although I have herein shown and described only one form of circuit controlling means embodying my invention, it is understood that various changes and modifications may be made therein within the scope of the appended claims without departing from the spirit and scope of my invention.

Having thus described my invention, what I claim is:

1. Circuit controlling means for at times connecting external circuits to the internal circuits of a device and for modifying the internal circuits upon disengagement of the external circuits from the internal circuits, said means comprising a plug having contact members adapted to be connected with the external circuits, a supporting member secured to said device for loosely receiving said plug, removable means for securing said plug in a fixed position in said supporting member, movable terminal posts mounted on said device and biased to positions in which they will engage the contact members of said plug part when said plug part is secured in place in said supporting member with sufficient force to forcibly eject said plug part from said supporting member upon removal of the securing means, and contacts on said device connected with the internal circuits of the device and operated to one position or another by the movement of one of said terminal posts according as said plug is in place within or is ejected from said supporting member.
2. Circuit controlling means for at times connecting external circuits to the internal circuits of a device and for modifying the internal circuits upon disengagement of the external circuits from the internal circuits, said means comprising

a plug having contact members adapted to be connected with the external circuits through the medium of flexible leads and a plug receptacle, a supporting member secured to said device for receiving said plug, said plug being provided with a transversely extending hole adapted to align with other holes provided in said supporting member when said plug is in place in said supporting member, a removable pin extending through the hole in said plug and the holes in said supporting member to secure said plug in place in said supporting member, movable terminal posts mounted on said device and adapted to contact the contact members in said plug when said plug is in place in said supporting member, means biasing said terminal posts to their contact making positions with sufficient force to forcibly eject said plug from said supporting member upon removal of said pin, and contacts connected to certain ones of said terminal posts and to the internal wiring of said device and operated to different positions by movement of said terminal posts.

3. Circuit controlling means for disengaging external electrical circuits of an electrically controlled missile and for operating internal circuits of the missile when the missile is released toward its ultimate target, said means comprising a plug consisting of a cylindrical body of insulating material provided with holes extending longitudinally therethrough and with other holes extending transversely therethrough, and with a longitudinal groove in its outer edge, the longitudinally extending holes being unevenly spaced and being counterbored at one end to form recesses, contact pins extending through the longitudinal holes in said plug and provided at one end with enlarged heads disposed in said recesses and forming contact buttons and secured at the other end to projecting contact fingers adapted to be plugged into a plug receptacle the contact members of which are connected to said external electrical circuits by a flexible cable, a cylindrical supporting member secured to the outer side of the missile and dimensioned to loosely receive said plug and provided with holes adapted to align with the transverse holes in said plug when said plug is in a predetermined position within said supporting member and with a pin cooperating with the groove in said plug to prevent said plug from being inserted into said supporting member except in one angular position, a seal pin fitting the one set of holes in said supporting member and the aligned hole in said plug to at times secure said plug in place in said supporting member, the other transverse hole in said plug and the aligned holes in said supporting member being provided for the reception of an arming wire for at times securing said plug in said supporting member upon removal of said seal pin, and terminal posts in said device adapted to engage and make contact with the contact buttons of said plug when said part is secured within said supporting member, said terminal posts being connected with the internal wiring of the missile and being biased to their contact making positions with sufficient force to forcibly eject said plug from said supporting member upon removal of the seal pin and arming wire.

4. Circuit controlling means for disengaging external electrical circuits of an electrically controlled missile and for operating internal circuits of the missile when the missile is released toward its ultimate target, said means comprising a plug consisting of a cylindrical body of insulating material provided with holes extending longitudi-

nally therethrough and with other holes extending transversely therethrough, and with a longitudinal groove in its outer edge, the longitudinally extending holes being unevenly spaced and being counterbored at one end to form recesses, contact pins extending through the longitudinal holes in said plug and provided at one end with enlarged heads disposed in said recesses and forming contact buttons and secured at the other end to projecting contact fingers adapted to be plugged into a plug receptacle the contact members of which are connected to said external electrical circuits by a flexible cable, a cylindrical supporting member secured to the outer side of the missile and dimensioned to loosely receive said plug and provided with holes adapted to align with the transverse holes in said plug when said plug is in a predetermined position within said supporting member and with a pin cooperating with the groove in said plug to prevent said plug from being inserted into said supporting member except in one angular position, a seal pin fitting the one set of holes in said supporting member and the aligned transverse hole in said plug to at times secure said plug in place in said supporting member, the other transverse hole in said plug and the aligned holes in said supporting member being provided for the reception of an arming wire for at times securing said plug in said supporting member upon removal of said seal pin, and terminal posts in said device adapted to engage and make contact with the contact buttons of said plug when said plug is secured within said supporting member, said terminal posts being connected with the internal wiring of the missile and being biased to their contact making positions with sufficient force to forcibly eject said plug from said supporting member upon removal of the seal pin and arming wire.

5. Circuit controlling means for at times connecting external circuits to the internal circuits of a device and for modifying the internal circuits upon disengagement of the external circuits from the internal circuits, said means comprising a plug having contact members adapted to be connected with the external circuits, a supporting member secured to said device for loosely receiving said plug in a fixed position in said supporting member, movable terminal posts mounted on said device and biased to positions in which they will engage the contact members of said plug when said plug is secured in place in said supporting member with sufficient force to forcibly eject said plug from said supporting member upon removal of the securing means, a movable contact finger mounted in said device and electrically and mechanically connected at one end with one of said terminal posts, and a fixed contact finger cooperating with said movable contact finger to form a contact for modifying the internal circuits of said device upon disengagement of said plug from said terminal posts.
